BOILER

Franklin A. Ferguson and Edgar C. Desjardins,
Westfield, Mass., assignors to The H. B. Smith
Company, Incorporated, Westfield, Mass., a
corporation of Massachusetts

Application August 3, 1940, Serial No. 350,856

7 Claims. (Cl. 122—225)

This invention relates to an improvement in boilers more particularly in sectional boilers of the well known Mills type, the sections of which have vertically extending water tubes in their upper parts which provide maximum heat absorption, free flowing circulation and quicker steaming.

One feature of this invention resides in the formation of the partitions between upper and lower side flues as integral parts of the sections, such partitions being in the form of dry fins or cored water tubes or a combination of tubes and fins.

Another feature of this invention resides in the provision upon the vertical water tubes of vertical fins thereby increasing the heat absorbing surface and directing the flow of the combustion gases.

Still another feature of this invention resides in the mounting within the rearmost section of a tankless water heater.

These and other features of the invention are included in the embodiment of this invention set forth in detail in the following description and illustrated in the accompanying drawings in which:

Fig. 1 is a perspective view with parts broken away of a boiler embodying this invention;

Fig. 2 is a front elevation of the upper portion of one of the leg sections of said boiler;

Fig. 3 is a cross-sectional view through two adjacent leg sections taken along the line 3—3 in Fig. 2;

Fig. 4 is a similar cross-sectional view taken along the line 4—4 in Fig. 2;

Fig. 5 is a cross-sectional view taken along the line 5—5 in Fig. 1;

Fig. 6 is a front elevation of the rear section of the boiler with parts broken away;

Fig. 7 is a side view of such section the panel of the tankless heater being removed; and

Fig. 8 is a view in side elevation of a portion of the rear end of the boiler with parts broken away.

The boiler 15 selected as an illustration of this invention comprises a plurality of leg sections 16, a rear section 17, and a casing 18. The sections are securely bolted into contact and register with each other. Mounted upon the front wall of the casing 18 are doors 19 and 20 while mounted upon the rear wall thereof is a smoke stack 21. Each leg section 16 is of cast iron and comprises a pair of vertical tubular legs 22 which merge into a horizontal compartment 23 and thus enclose the firebox 24 on three sides.

Through the compartment 23 and at right angles thereto extend side flues 25, 26 and a plurality of radiating tear-shaped passages 27, three such passages being here shown. The compartments 23 are joined by nipples 28 into a continuous system. The upper and lower side flues are separated by partitions 30 preferably as here shown integral parts of the section. The partition 30 comprises a cored tube 31 and fins 32 diametrically projecting from the tube. The mouth of the lower flue 26 is enclosed by a bead 33 which extends along the surface of the section near the outer edge thereof, by beads 34 and 35 and by the fin 32. As shown in Figs. 4 and 8, the edges of the fins 32 do not come into contact when the sections are assembled so that gases may pass between them from the flue 25 to the flue 26 and thus heat portions of the boiler surfaces heretofore inaccessible.

Mounted between the passages 27 are fins 40 which are here shown (Fig. 3) as integral projections from a tubular core 41. These fins act to direct the gases arising from the fire box into the flues 25 and also increase the heat absorbing surface in the path of the gases.

The rear section 17 which closes the rear end of the fire box is provided with flues 45 which are in substantial alignment with the lower flues 26 of the leg sections. Above the flues 45 is a chamber 47 jointed to the system by a nipple (not shown) similar to nipples 28. The front and rear walls of the chamber are connected by flat straps 48. Mounted within the chamber 47 is a water heating unit 50, one, for example, of the type known in the trade as a tankless heater, and comprising a plurality of lengths of pipe 51 through which a stream of water is passed from inlet 52 to outlet 53. The chamber 47 being part of the water system, the water in the lengths of pipe is heated. The pipe lengths preferably but not necessarily extend transversely of the section, as shown in the drawing. The lengths are carried by a plate 54 which is removably secured to the section wall and are so arranged that they 45 straddle the straps 48 (Fig. 6). Some of the gases which rise from the rear end of the fire box between the rear section 17 and the leg section 16 adjacent to its escape past the fins 32 into the flues 45 and thence directly to the smoke stack 21, thus making active surfaces which are normally more or less inactive and creating a draft which improves the combustion of the fuel.

The doors 19 are preferably sealed to prevent escape of gases from the boiler. Thus, as shown in Fig. 5, the door frames 55 are provided with

ribs 56 and the door panels are provided with recesses 57 which receive such ribs. Preferably a packing 58 of asbestos or other suitable material is laid in the recesses to seal the doors when tightly closed by nuts, bolts or the like.

As in all boilers of this type the draft from the stack establishes and maintains a flow of gases forwardly through the passages formed by the flues 25 to the front of the boiler, thence downwardly through the space or connecting duct defined by the outer face of the front section and the front wall of casing 18 (Fig. 1), and rearwardly through the passages formed by the flues 26 and 45 to the stack or smoke hood 21. The gases which rise from the fuel in the fire box 24 into the spaces formed between each two adjacent sections freely enter this flow through the flues 25. The mouths of the flues 26 are partially enclosed by the beads 34 and 35 and the fins 32. Hence only such gases as are drawn in by the flow through the lower passages enter the flues 26 between the fins 32 (see Figs. 4 and 8) the beads 34 and 35 being in contact (see Fig. 3). The fins 40 deflect the rising gases toward the open flues.

While one embodiment of this invention has been shown and described in detail, it will be understood that the invention is not limited thereto and that other embodiments of the invention may be made without departing from the spirit and scope thereof.

We claim:

1. A boiler comprising a plurality of vertical sections assembled in contact along the top and side edges and spaced apart within said edges, each section, in advance of the rear section, comprising water legs and a horizontal compartment connecting said legs and enclosing therewith the fire box on three sides from which box gases rise into the spaces between the sections, and having pairs of flues through said compartment at right angles thereto and arranged one above the other, the mouths of the lower flues being enclosed at their bottom and sides by beads projecting outwardly from the surfaces of the compartments and by beads at the edges of the sections, which flues, when the sections are assembled, register to form passages extending longitudinally through the boiler, and nipples connecting the compartments of the sections, a casing adjoining the front section so as to provide a connecting duct between the passages formed by the upper and lower flues, the passage formed by the lower flues being in communication with the smoke stack whereby the gases rising from the fire box into the spaces between the sections enter the upper flues and travel forwardly through the upper passage, downwardly through said connecting duct and rearwardly through the lower passage to the smoke stack, and fins carried by said sections which deflect the gases toward said upper flues.

2. A boiler comprising a plurality of vertical sections assembled in contact along the top and side edges and spaced apart within said edges, each section, in advance of the rear section, comprising water legs and a horizontal compartment connecting said legs and enclosing therewith the fire box on three sides from which box gases rise into the spaces between the sections, and having pairs of flues through said compartment at right angles thereto and arranged one above the other, nipples connecting the compartments of the sections, a partition separating said flues, and outwardly projecting fins on the partition, the

mouths of the lower flues being enclosed at their bottoms and sides by beads projecting outwardly from the surfaces of the compartments, and by beads at the edges of the sections, the mouths of the lower flues being partially enclosed at the top by said fins, which flues, when the sections are assembled, register to form passages extending longitudinally through the boiler, a casing adjoining the front section so as to provide a connecting duct between the passages formed by the upper and lower flues, and the passage formed by the lower flues being in communication with the smoke stack, whereby the gases rising from the fire box into the spaces between the sections enter the upper flues freely and the lower flues between said fins and travel forwardly through the upper passage, downwardly through said connecting duct and rearwardly through the lower passage to the smoke stack.

3. A boiler comprising a plurality of vertical sections assembled in contact along the top and side edges and spaced apart within said edges, each section, in advance of the rear section, comprising water legs and a horizontal compartment connecting said legs and enclosing therewith the fire box on three sides from which box gases rise into the spaces between the sections, and having pairs of flues through said compartment at right angles thereto and arranged one above the other, nipples connecting the compartments of the sections, the mouths of the upper flues terminating at the surfaces of the sections and the mouths of the lower flues being enclosed at their bottoms and sides by means projecting outwardly from such surfaces and by means projecting outwardly from the edges of the sections, which flues, when the sections are assembled, register to form passages extending longitudinally through the boiler, a casing adjoining the front section so as to provide a connecting duct between the passages formed by the upper and lower flues, the passage formed by the lower flues being in communication with the smoke stack, whereby the gases rising from the fire box into the spaces between the sections enter the upper flues freely and travel forwardly through the upper passage, downwardly through said connection duct and rearwardly through the lower passage to the smoke stack.

4. A boiler comprising a plurality of vertical sections assembled in contact along the top and side edges and spaced apart within said edges, each section, in advance of the rear section, comprising water legs and a horizontal compartment connecting said legs and enclosing therewith the fire box on three sides from which box gases rise into the spaces between the sections, and having pairs of flues through said compartment at right angles thereto and arranged one above the other, nipples connecting the compartments of the sections, the mouths of the upper flues terminating at the surfaces of the sections and the mouths of the lower flues being enclosed at their bottoms and sides by means projecting outwardly from such surfaces and by means projecting outwardly from the edges of the sections, which flues, when the sections are assembled, register to form passages extending longitudinally through the boiler, a casing adjoining the front section so as to provide a connecting duct between the passages formed by the upper and lower flues, the passage formed by the lower flues being in communication with the smoke stack, whereby the gases rising from the fire box into the spaces between the sections enter the upper

flues freely and travel forwardly through the upper passage downwardly through said connecting duct and rearwardly through the lower passage to the smoke stack, and fins carried by said sections which deflect the gases toward said upper flues.

5. A boiler comprising a plurality of vertical sections assembled in contact along the top and side edges and spaced apart within said edges, each section, in advance of the rear section, comprising water legs and a horizontal compartment connecting said legs and enclosing therewith the fire box on three sides from which box gases rise into the spaces between the sections, and having pairs of flues through said compartment at right angles thereto and arranged one above the other, the mouths of the upper flues terminating at the surfaces of the sections and the mouths of the lower flues being enclosed at their bottoms and sides by means projecting outwardly from such surfaces and by means projecting outwardly from the edges of the sections, which flues, when the sections are assembled, register to form passages extending longitudinally through the boiler, a casing adjoining the front section so as to provide a connecting duct between the passages formed by the upper and lower flues, the rear section comprising a horizontal compartment and having a flue which registers with said lower flues and through which communication of the lower passage with the smoke stack is provided, nipples connecting the compartments of the sections, and a water heating unit mounted within the compartment of said rear section.

6. A boiler comprising a plurality of vertical sections assembled in contact along the top and side edges and spaced apart within said edges, each section, in advance of the rear section, comprising water legs and a horizontal compartment connecting said legs and enclosing therewith the fire box on three sides from which box gases rise into the spaces between the sections, and having at each side a pair of flues through said compartment at right angles thereto and arranged one above the other, the mouths of the upper flues terminating at the surfaces of the sections and the mouths of the lower flues being enclosed at their bottoms and sides by means projecting outwardly from such surfaces and by means projecting outwardly from the edges of the sections, which flues, when the sections are assembled, register to form passages

extending longitudinally through the boiler, the rear section comprising a horizontal compartment and having a pair of flues below said compartment which register with said lower flues and through which communication of the lower passages with the smoke stack is provided, a casing adjoining the front section so as to provide a connecting duct between the passages formed by the upper and lower flues, and nipples connecting the compartments of the sections, whereby the gases rising from the fire box into the spaces between the sections enter the upper flues and travel forwardly through the upper passages, downwardly through said connecting duct and rearwardly through the lower passages to the smoke stack.

7. A boiler comprising a plurality of vertical sections assembled in contact along the top and side edges and spaced apart within said edges, each section, in advance of the rear section, comprising water legs and a horizontal compartment connecting said legs and enclosing therewith the fire box on three sides from which box gases rise into the spaces between the sections, and having at each side a pair of flues through said compartment at right angles thereto and arranged one above the other, the mouths of the upper flues terminating at the surfaces of the sections and the mouths of the lower flues being enclosed at their bottoms and sides by means projecting outwardly from such surfaces and by means projecting outwardly from the edges of the sections, which flues, when the sections are assembled, register to form passages extending longitudinally through the boiler, the rear section comprising a horizontal compartment and having a pair of flues below said compartment which register with said lower flues and through which communication of the lower passages with the smoke stack is provided, a casing adjoining the front section so as to provide a connecting duct between the passages formed by the upper and lower flues, and nipples connecting the compartments of the sections, whereby the gases rising from the fire box into the spaces between the sections enter the upper flues and travel forwardly through the upper passages, downwardly through said connecting duct and rearwardly through the lower passages to the smoke stack, and fins carried by said sections which deflect the gases toward said upper flues.

FRANKLIN A. FERGUSON.
EDGAR C. DESJARDINS.
